(57) **CLAIM**

We claim the ornamental design for lock device, as shown and described.

DESCRIPTION

FIG. 1 is a front perspective view of a lock device;
FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a bottom-front perspective view of the lock device,
shown in an alternate state with the cover in an open state;
and,

FIG. 10 is a left side view thereof.

1 Claim, 5 Drawing Sheets
